(57) **CLAIM**

The ornamental design for a track rail for a movement guide device, as shown and described.

DESCRIPTION

FIG. 1 is a top isometric view of a track rail for a movement guide device showing my new design;

FIG. 2 is a bottom side isometric view thereof;

FIG. 3 is a front elevational view thereof;

FIG. 4 is a rear elevational view thereof;

FIG. 5 is a left side elevational view thereof, the right side elevational view being identical thereto;

FIG. 6 is a top plan view thereof;

FIG. 7 is a bottom plan view thereof;

FIG. 8 is an enlarged view of portion 8 of FIG. 1;

FIG. 9 is an enlarged view of portion 9 of FIG. 2;

FIG. 10 is an enlarged, left side elevational view thereof; and,

FIG. 11 is an enlarged cross-sectional view taken along line 11-11 of FIG. 6.

The broken lines in the drawings depict portions of track rail for a movement guide device and form no part of the claimed design. The dot-dash broken lines in the drawings illustrate the bounds of the claim and form no part thereof.
